TELEGRAPH KEY

Charles M. Hayman, Brooklyn, N. Y.

Application June 7, 1945, Serial No. 598,065

17 Claims. (Cl. 178—102)

1

The invention relates in general to a manually actuated circuit closer of the compound lever type designed for rapidly closing and opening one or two electric circuits for use wherever such circuits are used, and the invention specifically relates to an improvement in telegraph or transmitting keys used in the transmission of signals included in a two wire or three wire alarm system.

The primary object of the invention is to provide an improved and simplified form of circuit closer of the class described.

The invention features in a new form of telegraph key a system of levers operating between the manually depressed finger piece and the electric contacts controlling the circuit and which levers are disposed, in overlapping relation, to economize in space disposition and interconnected to effect a quick and positive actuation of the contacts both in their contacting and in their separating action and to effect a prolonged time dwell in the inter-engagement of the contacts after contact is made.

Various other objects and advantages of the invention will be in part obvious from an inspection of the accompanying drawings and in part will be more fully set forth in the following particular description of one form of telegraph key embodying the invention and the invention also consists in certain new and novel features of construction and combination of parts hereinafter set forth and claimed.

In the accompanying drawings,

Fig. 1 is a plan view which may be illustrative of either the Fig. 2 or Fig. 4 form of the invention.

Fig. 2 and Fig. 3 are views in side elevation of one embodiment of the invention when utilized in connection with either one of two external circuits controlled thereby;

Fig. 2 showing the parts with the control key in its normal elevated inoperative position and at which time a first circuit is open and a second circuit closed when the main supply switch is closed;

Fig. 3 showing the relation of the parts with the control key depressed under manual load and with the first circuit closed and the second circuit open;

Fig. 4 is a view similar to the showing of Fig. 3 of another form of the invention particularly designed to control a single external and normally open circuit; and

Fig. 5 is a detail partly in section of the swinging bracket particularly illustrating the Figs. 2-3 form of the invention.

2

In the drawings and referring indifferently to both of the embodiments shown in Figs. 2 and 4 there is disclosed a flat plate-like base 9 of black Bakelite or other insulating material designed to be mounted upon and secured to a metallic block 10 or similar form of support. An upstanding fulcrum forming support 11 in the form of two flat posts 12 and 13 is located on the block 10 adjacent its midlength and extends through recesses provided therefor in the insulating plate 9. Located on top of the base at its forward end 14 and secured thereto is a flat bearing plate 15 provided with a pair of upstanding parallel semi-circular cheek plates 16 and 17 and between which is mounted a flat cylindrical stainless steel roller bearing 18 journaled for free rotary movement on pin 19 extending between the cheek plates. The underside of the base beneath the roller bearing is recessed as shown at 20 and a screw 21 extends through the recess and by means of a nut 22 in the recess is secured in place and acts as a binding screw to secure thereto an electric lead 23 forming part of the circuit controlled by the instrument.

A fixed base contact 24 is secured to the base 9 and support 10 adjacent the rear end 25 by screwing it on to the upper end of a long screw 26 passed through the base insulated therefrom by a sleeve 23 and washer 24 of insulating material. Screw 26 is secured in place by a binding nut 27 located within a recess 28 formed on the underside of the support 10. Screw 26 also forms a binding screw for connecting the companion lead 29 to the base contact 24.

A long rugged key bar 30 is pivoted intermediate its length on a fulcrum pin 31 carried by the support 11 at its upper end and is disposed to extend from front to rear of the base 10. The key bar is provided at its forward end with a depressible finger piece 32 which projects forwardly of the advanced end 14 of the base and in general this part of the key bar is of conventional design. The portion 33 of the key bar between the fulcrum pin 31 and the finger piece 32 will be referred to hereinafter as a lever of the second class because both its power arm and its work arm are on the same side of the fulcrum 31. The lever 33 is provided at a point much nearer the fulcrum pin 31 than the finger piece 32 with a swinging bracket 34 pivoted to the lever on pin 35 and depending therefrom towards the base 10 and the bearing plate 15.

The bracket 34 forms the fulcrum portion of a movable contact lever 35, the forward portion 56 of which constitutes a relatively short arm form-

ing a stop lever 36 which overlaps and at all times is in bearing engagement with the periphery of the roller bearing 18. The right end of the lever 35' as shown in Fig. 5 is sandwiched between an insulating plate 91 and a terminal plate 95, and an insulating plate 92 lies between the terminal plate 95 and the stop lever 36. The plates are secured by screws 96. The stop lever is maintained in engagement with the roller bearing by means of a short compression spring 37 at all times under load having its lower end seated in a recess 38 provided therefor in the stop lever 36 as best shown in Fig. 5. A stop adjusting screw 39 is threaded through the lever arm 33 and acts to limit the upward swing of the contact lever 36 and acts to control the time duration while contact 42 engages contact 24. Lock nut 40 secures the screw 39 in its adjusted position.

The portion of the movable contact lever which extends rearwardly from the stop lever 36 is in the form of a long flat spring 41 which extends rearwardly through and past the support 11 and terminates at its rear end in a movable or floating contact 42 disposed in position when lowered from the position shown in Fig. 2 into the position shown in Figs. 3 and 4 to bear resiliently on the fixed base contact 24. The contacts 24, 90 and 42 are preferably formed of coin silver and the conductive parts are for the most part formed of brass.

A flexible braided conductor 43 has one end connected to the terminal plate 95 in electric contact with lever 35' and has its other end secured to the bearing plate 15 by means of the screw 21 in the Figs. 2 and 3 device and by a separate screw 45 in the Fig. 4 device.

In Fig. 4 a slightly different form of connection between the lever 35' and conductor 43 is provided. In this case the insulation plates 91 and 92 are omitted and the forward end of lever 35' is in direct electric contact with lever 36. The rear end of lever 36 is in turn connected to the upper end of conductor 43 by means of a screw 44.

At its rear end the key bar 30 is provided with a spacing screw 46 which bears on top of a wear block 47 screwed into the base 9 to locate the key bar 30 in its normal horizontal position as shown in Fig. 2 and thus to define the position assumed by the key bar under tension of spring 37 when free of the manual load on the finger piece 32. Likewise the key bar is provided with an adjustable contact screw 48 equipped at its lower end with a contact 90 for limiting the upward swing of the movable contact 42 as it retreats or bounces away from the fixed contact 24.

The disclosure particularly features the distance advantage developed by the compound lever arrangement shown for translating a short manual movement of the finger piece 32 into a long sweeping movement of the contact 42. Referring first to the power lever it is intended that its power arm be long as indicated by the distance $a-b$ as shown in Fig. 4 measured from the fulcrum 31 to the loci of finger pressures on the finger piece 32 and its work arm is intended to be relatively short as indicated by the distance $a-c$ measured between the fulcrums 35 and 31. Referring to the second lever 35' its power arm $c-e$ measures from the lever pin 35 to the slightly shifting point at which the stop lever 36 engages the roller bearing 18 which forms the shiftable fulcrum about which the movable contact lever swings. The work arm is relatively

long as indicated by the distance $d-e$ between the roller bearing 18 at any instant of time and the wiping contact 42. The distance advantage may therefore be indicated as the product of the distances

$$\frac{a-b}{a-c} \text{ and } \frac{c-e}{d-e}$$

It is particularly noted that the movement of the finger piece 32 over a relatively short arc of movement causes the movable contact 42 to move over a very much longer arc of movement in the same time interval as it shifts to and from its fixed companion.

In operation and assuming a manual pressure on the finger piece with the quick staccato action usual with telegraph operators the finger piece is lowered from the Fig. 2 position towards the Fig. 3 or Fig. 4 position over an extremely short distance. This causes the key bar 30 as a whole to swing about its central support provided by the fulcrum pin 31. This swinging movement has the effect of snapping the lever 33 downwardly thus lowering the bracket 34 and at the same time causing it to swing slightly towards the right from the position shown in Fig. 2. The right end of the movable contact lever 36 being resisted from downward movement by the roller bearing 18 causes the flat spring 41 forming the free end of lever 35' to slap the movable contact 42 into engagement with the flat top of the fixed contact 24. As the lever 35' thus swings from the position shown in Fig. 2 to the position shown either in Fig. 3 or 4, it also tends to shift slightly towards the roller bearing 35 in the direction of its own length and which movement is facilitated due to the fact that the roller bearing is free to turn clockwise at this stage of the operation. The left to right movement of the lever 41 as contact is made causes the top or movable contact 42 to wipe slightly from left to right across the top of the base contact 24. With the contacts interengaged as shown in Fig. 3 the circuit is completed from screw 21, bearing plate 15, conductor 43, terminal plate 95, lever 35' and movable contact 42 and therefrom through fixed contact 24 and screw 26 to complete the circuit through the circuit forming parts exterior to the key herein featured. Similarly the circuit can be traced in Fig. 4 except that conductor 43 leads to lever 36 and there through to lever 35'.

As the bracket 34 swings from left to right on the depression of the finger piece 32 as above described, the long flat spring 41 may bend or arc downwardly between its end supports 18 and 24 and is thus placed under tension during the instant of time the contacts are in engagement. This means that as soon as the load is released on the finger piece the flat spring in its tendency to recover itself shifts slightly from right to left thus wiping the moveable contact 42 across the face of the fixed contact 24 while the contacts are still in current transmitting relation.

Releasing pressure on the finger piece permits compression spring 37 to react between the key bar 30 and the moveable contact lever 36 to depress its right end and elevate its left end, thus snapping the moveable contact 42 away from its companion 24, and this movement continues until stopped by the contact 90 of the adjusting screw 48 and the parts are then restored to their set initial position shown in Fig. 2. The parts are then in position ready for the next actuation of the key.

By means of the device above described, it is possible to obtain by comparison with known forms of similar telegraph keys a faster operation due to the smaller travel of the finger piece and the avoidance of any necessity on the part of the operator to hold the key depressed as is required at present to insure a clean sending of the proper signal. The roller bearing form of fulcrum at 18 insures an easier and smoother operation; the contacts 24 and 42 as well as 42 and 90, are held together longer to insure a better current flow, thus resulting in accuracy in the transmission of the desired signal, especially noticeable where the device controls inked signals and spaces recorded on paper tape; a quicker breaking of the contacts insure a lessening of any arc which might tend to form between them on the breaking of the circuit, and because of this current of higher potential strength may be used. It is particularly noted that the contacts are of the wiping type, thus insuring a cleaner and better contact even after the device has been in use for a long time. It is a feature of this disclosure that the several operating parts are disposed in a vertical plane and as far as possible are made of the least possible width. In this way the device, as a whole is formed compact especially in its front to rear dimension, and can thus be accommodated in a space restricted by the presence of other instruments.

It is noted that the keybar 30 is at all times maintained by spring 37 in firm, mechanical pressing engagement with the bearing 18. By this means there is avoided any tendency of the levers to bounce the contacts and cause the chatter or double tap signal, and thus the key has a better feel to the operator than conventional forms of keys.

In the devices as thus far described the key is intended to operate a two wire normally open circuit system which, externally of the key, includes as shown in Figs. 2 and 5, a source of electric energy 49, a main supply control switch 50 and an apparatus 51, such as a signaling device for the operation of which the key herein featured is particularly designed.

The devices hereinbefore described can quite easily be modified from the showing of the simpler two wire form to accommodate it to a three wire system to open and close alternately two external circuits on each actuation of the key bar. This has been done in the case of the key shown in Figs. 2 and 3 largely by adding an additional terminal for supplying current direct to the key bar 30 and to a contact 90 associated therewith. For this purpose a third terminal forming screw 52 is passed through the support 10, is secured by nut 53 and has its upper end in screw threaded and electric contact with the support 11, and therethrough conducts current to the key bar 30 through pigtail 54 and thus to the adjustable screw 48 and its contact 90 which in this case forms a contact relatively fixed insofar as the flapping or floating contact 42 is concerned but actually shiftable in space with the movement of the key bar 30. This terminal screw 52 is connected to the battery circuit by conductor 55 and includes a second instrument 56 and which for the purpose of this disclosure may be considered as another signalling or equivalent device.

Referring to the situation as shown in Fig. 2 and where the key is in its normal elevated position, the circuit can be traced from the battery 49, switch 50 when closed, instrument 56, con-

ductor 55, screw 52, support 11, pigtail 54, lever 30, closed contacts 90 and 42, long flat spring lever 35, terminal plate 95, conductor 43, terminal 21 and conductor 23 back to the other side of the battery. At this time spring 37 is acting to maintain the contacts 42 and 90 in bearing engagement and which arrangement has the advantage of maintaining a good closed contact when the key is in its normal inactive and at rest position. Under these normal conditions the instrument 56 is energized and thus active and this instrument remains active so long as the key is in its elevated normal position shown in Fig. 2. The normally open circuit which includes the other instrument 51 is of course broken at this time because the contacts 24 and 42 are in their spaced apart relation and this will be the condition of the parts controlling instrument 51 so long as the key bar remains in its normal horizontal position shown in Fig. 2.

Referring to the situation as shown in Fig. 3 the key bar has turned clockwise about its fulcrum 31 by manually load slightly depressing the finger piece 32 as previously indicated. This has the effect of lowering contact 42 from its normal position engaging contact 90 into a lowered position engaging contact 24. The current can now be traced from battery through the instrument 51, conductor 29, terminal screw 26, contacts 30, 24-42, lever 35, terminal plate 95, conductor 43, terminal screw 21 and conductor 23 back to the other side of the battery. At this time then the instrument 51 in this normally open but momentarily closed circuit becomes active and the current which includes the instrument 56 is of course now broken because the contacts 42 and 90 are in their spaced apart relation. This means that instrument 51 functions just so long as the key is depressed and that instrument 56 is restored to its normal functioning status as soon as the manual load is removed from the finger piece 32 and spring 37 is permitted to restore the parts to their normal positions.

It has been found that the breaking of the contacts 90 and 42 is faster than the breaking of the contacts 42 and 24 when used to close and open the normally open circuit herein disclosed due to the contacts 90 and 42 moving in opposite directions when finger piece 32 is depressed.

50 I claim:

1. A key controlled circuit closer comprising a base provided with an upstanding support, a key bar fulcrumed to said support and provided at one end with a manually depressible finger piece, 55, a swinging bracket pivoted to the key bar between its fulcrum and the finger piece and depending from the key bar, a contact lever having one end secured to the bracket, extending slightly forward from its fulcrum towards the finger piece 60 and forming a stop lever and said contact lever having another arm formed mainly of a long, flat spring extending from front to rear beyond the key bar fulcrum and provided at its rear free end with a movable wiping contact, a roller bearing carried by the base, located in the path of movement of the stop lever as it is lowered by the depression of the finger piece and forms a rotatable stop about which the stop lever swings as a fulcrum, a compression spring between the 70 key bar and stop lever tending at all times to maintain the stop lever in pressing engagement to said bearing, and a fixed contact carried by the base disposed in the path of movement of the movable contact and coacting therewith to change the status of a circuit when the movable

contact is actuated by the depression of the finger piece, said key bar, stop lever, roller bearing and movable and fixed contacts being disposed in a vertical plane.

2. In a circuit closer, the combination of two levers in parallel superposed relation, the upper lever forming a key bar and constituting a lever of the second class fulcrumed at one end and provided with a finger piece at the opposite end, the second lever being of the third class pivoted intermediate its ends to a point of the key bar between its fulcrum and its finger piece end, said second lever having a relatively long arm provided at its end with a movable contact and a relatively short arm, and a fixed stop at all times engaged by the short arm and forming a fulcrum about which the second lever swings when the finger piece is actuated and a fixed contact disposed in the path of movement of the movable contact and engaged thereby on the depression of the finger piece to effect the status of a circuit through the two contacts.

3. The structure defined in claim 2 in which the long arm of the second lever is a flat spring.

4. The structure defined in claim 2 in which a compression spring reacting between the key bar and the short arm of the second lever maintains the short arm in engagement with the fixed stop and tends to return the key bar to its elevated normally inoperative circuit breaking position.

5. The structure defined in claim 2 and in which the key bar is provided with adjustable stops for limiting its swinging movement in both directions.

6. The structure defined in claim 2 and in which the key bar is provided with an adjustable stop limiting the movement of the movable contact in its direction away from the fixed contact.

7. In a key controlled circuit closer, the combination of a pair of coacting contacts, one being fixed and the other movable, a floating lever on one end of which the movable contact is carried, a second lever above and paralleling the first lever provided at one end with a finger piece, and a fixed member which constitutes a fulcrum for the other end of the floating lever, said floating lever being free to slide over the fixed member, a pivotal connection between the levers located materially closer to the fixed member than to the movable contact, a spring reacting between the two levers biased to maintain the floating lever at all times in bearing engagement with the fixed member and to elevate the finger piece, said pivotal connection interconnecting the levers to provide a distance advantage for causing a sweeping movement of the movable contact over a relatively long arc of movement into its circuit closing engagement with the fixed contact by virtue of a movement of the finger piece over a relatively short arc of movement.

8. An electric circuit closer including a fixed and a movable contact, means for effecting a quick engagement and disengagement of the contacts at will, said means including a system of interconnected levers, one fulcrumed to turn about a fixed axis and forming a pivoted key bar provided at one end with a finger piece for actuating the same and the other fulcrumed to turn about an axis fixed to the key bar between its fulcrum and its finger piece end thereof, the portion of said other lever between its contact and its connection with the first named lever being flexible so as to be bendable by the continued action of the first lever after the contacts have been brought into engagement thereby, the ful-

crum points of the levers being related to provide for the finger piece lever a longer power arm than work arm, and for the other movable contact lever a shorter power arm than work arm thereby to cause the system to provide a distance advantage whereby a slight movement of the finger piece will cause a materially longer movement of the movable contact into a wiping engagement with its companion.

10. In a device of the class described, the combination of a pair of interconnected levers in superposed relation, the upper lever forming a lever of the second class and having a relatively long power arm provided at one of its ends with manually energized means for actuating the same and a relatively short work arm, both arms being on the same side of the fulcrum, the lower lever being a lever of the third class having a relatively short power arm and a relatively long work arm at least a portion of which is flexible, one end of the work arm of the upper lever coinciding with one end of the power arm of the lower lever and pivotally connected, a movable contact carried by one end of the long work arm of the lower lever, a fixed stop disposed in the path of movement of the other end forming a fulcrum for the lower lever and a fixed contact disposed in the path of movement of the movable contact and said upper lever acting after the contacts have inter-engaged to bend the flexible portion of the lower lever.

11. In a telegraph key for transmitting signals in accordance with a code employing a variable number of dots, the combination of a base, a fixed contact carried by the base, a fixed stop carried by the base, a first lever having a movable contact on one arm thereof for fixedly engaging the fixed contact and its other arm slidably engaging the fixed stop as a shiftable fulcrum about which it rocks, and a second lever overlapping the first lever at all times in the same plane therewith and to which the first lever is pivoted, a spring reacting between the levers to maintain said other arm slidably engaging the fixed stop, the fulcrums of said levers being in longitudinally spaced apart relation and said second lever provided at one end thereof with a finger piece for maintaining the contacts in their circuit closing position so long as the finger piece is disposed in its circuit closing position.

12. In a device of the class described, the combination of a base, a support upstanding from the base, an actuating lever fulcrumed to the support, a contact lever underlapping the actuating lever, a bracket pivoted to the actuating lever and depending therefrom, said contact lever including a flat spring secured at one end to the bracket and having a floating contact rigidly fixed to its other end, a fixed contact carried by the base and disposed in the path of movement of the floating contact, said fixed and floating contacts coacting to form a circuit closer for an electric circuit, a fulcrum forming stop carried by the base and disposed in the path of movement of the contact lever at its bracket end, a spring reacting between the actuating lever and the contact lever for maintaining the bracket end of the contact lever at all times in firm bearing engagement with the stop irrespective of the position of the floating contact and biased to move the floating contact away from its associated fixed contact and into its normal breaking position when permitted to do so by the elevation of the actuating lever in a direction away from the fulcrum forming stop.

12. In a device of the class described, the combination of a base, a support carried by the base, a key lever pivoted adjacent its midlength to the support and provided at one end with a finger piece, a contact carried by the key lever adjacent its other end and shiftable therewith, a fixed contact carried by the base and located opposite the shiftable contact, a second lever fulcrumed intermediate its ends to the key lever and provided at one end with a floating contact for engaging selectively the shiftable contact when moved in one direction and for engaging the fixed contact when moved in the opposite direction, a stop carried by the base and engaged by the end of the second lever opposite the end provided with the floating contact to lower the same from the shiftable contact to the fixed contact whenever the finger piece is depressed and means reacting between the contact lever and the key lever tending to maintain its finger piece end in elevated position.

13. In a device of the class described, the combination of a support, two levers superposed in parallel relation, the upper lever fulcrumed to the support and provided at its forward end with a compressible finger piece, the lower lever pivoted to, supported from, and thus fulcrumed to the upper lever between its fulcrum and its finger piece, the lower lever having a relatively short arm extending forwardly of its fulcrum and a relatively long rearwardly extending arm, a stop disposed in the path of movement of the relatively short arm to rock the same on the depression of the finger piece, said rearwardly extending arm provided at its rear end with a floating contact forming the movable element of a circuit closer, a relatively fixed contact of said circuit closer disposed in the path of movement of the movable contact element, a spring reacting between the levers and biased when free of manual load on the finger piece to elevate the movable contact element away from the fixed contact element and reacting through the short arm to elevate the forward end of the upper lever into its normal elevated position, the upper lever provided with an adjustable member engaged by the floating contact when elevated into engagement therewith by the spring affected elevation of the finger piece end of the upper lever.

14. In a telegraph key, the combination of a support, a key lever pivoted to the support, a second lever pivoted to the key lever and provided at one end with a double faced contact movable in one direction by the depression of the key lever and movable in the opposite direction by the elevation of the key lever, a pair of contacts, one being fixed and engaged by the double faced contact when moving in one direction and the other carried by the key lever and engaged by the double faced contact when moving in the opposite direction.

15. A telegraph key for sending a sequence of controlled dots and dashes, including a support, a contact fixed to the support, a co-acting floating contact above the fixed contact, manual actuated means for moving the floating contact positively into and from its circuit closing engagement with the fixed contact and for controlling the time lapse in which the floating contact is held in such circuit closing position, said means including a key bar pivoted to the support for rocking movement about a fixed axis, a contact lever pivoted intermediate its length to the key bar in offset relation to its fulcrum and including a flexible portion having a free end, the floating

contact being fixed to the free end of the flexible portion and a stop disposed in the path of movement of the other end of the contact lever and on which it is free to slide whereby on the depression of the key bar the contact lever swings about the stop as a fulcrum, first to bring the floating contact downwardly into bearing engagement with the fixed contact and thereafter on the continued depression of the key bar to bend the flexible portion of the contact lever in the part thereof between the key bar and the floating contact engaging the fixed contact, to hold the floating contact to the fixed contact so long as the key bar is so held depressed.

16. In a telegraph key of the type used to send dot and dash code, such as the Morse code, the combination of a base unit formed of conductive material including a base member and an upstanding fulcrum support, a second unit formed of conductive material, secured to the base unit on one side of the support and insulated therefrom and including a bearing plate carrying a fulcrum forming bearing and a binding post electrically connected, a third unit on the opposite side of the support and including a fixed contact and associated binding post carried by and insulated from the base unit, a key-bar of conductive material fulcrumed adjacent its mid length to the fulcrum support and provided on one side thereof with a contact shiftable therewith and on the other side thereof with a bracket pivoted to the key-bar and depending therefrom, a second lever of conductive metal underlapping the key bar and secured to the depending bracket to turn therewith, with one end of the second lever at all times in bearing engagement with the bearing plate fulcrum and provided at its other end with a floating contact shiftable by the swinging of the levers between the fixed contact and the shiftable contact, and a flexible conductor electrically connecting the second unit with the second lever.

17. In a telegraph key, the combination of a unit formed of conductive material including a base member provided with a first binding post and with an upstanding fulcrum support, a fulcrum-forming bearing secured to the base member and insulated therefrom, a second binding post carried by the base member insulated therefrom and connected mechanically and electrically to the bearing, a fixed contact and associated third binding post carried by the base member and insulated therefrom, a key bar provided with a finger piece at one end, fulcrumed adjacent its mid length to the fulcrum support and provided on one side thereof and opposite the fixed contact with a shiftable contact and on the other side of the support with a swinging bracket pivoted thereto, a second lever having a portion adjacent one end secured to the bracket, one end of the second lever overlapping and engaging the bearing as a fulcrum, a flexible conductor electrically connecting the second lever with the bearing plate and its associated binding post, a floating contact carried by the other end of the second lever shiftable by the actuation of the key bar from the fixed contact to the shiftable contact and operable in one position engaging the fixed contact to complete the circuit from the fixed contact through the second lever to the bearing plate and its associated binding post and in another position engaging the shiftable contact to complete the current from the bearing and its associated binding post through the second

lever through a portion of the key bar to the base member and its associated binding post.
